LINE INDICATOR

Bonnie E. Van Alstyne, San Francisco, Calif.

Application September 20, 1938, Serial No. 230,844

4 Claims. (Cl. 120—33)

My invention relates to improvements in a line indicator, and it consists of the combinations, constructions and arrangements hereinafter described and claimed.

An object of my invention is to provide an improvement over the form of the device shown in my Patent No. 2,130,750, issued September 20, 1938. In the patented device, spring clips are used for securing the line indicator guide to the side of the notebook. These clips space the guide a slight distance from the side of the notebook. In my present invention a different form of clip is used and this will permit the guide to be disposed adjacent to the edge of the book.

A further object of my invention is to provide a line indicator which may be attached to a notebook for holding the book in an upright position and for also indicating the line to be copied. The device may be secured to a sidewise opening book when it is desired to copy information from the book. When the device is secured to a sidewise opening book, it may be attached to a single leaf of the book rather than to the cover and this will permit the page to be turned while the device is still attached thereto. The line indicator is slidable on a guide and when the page is turned, the indicator may be moved to the top of the guide and swung over to the other side and thus be used for copying information from the other side of the page. In this way, the device may be attached to one page at a time and will permit both sides of the page to be copied without the necessity of removing the device from the page.

The line indicator has an extension that may be secured thereto when it is desired to copy information from a large chart or sheet. When a large chart is used, the device is attached to the back of a notebook and the notebook back also carries an arm that supports the back of the chart and aids in holding it in proper position.

Other objects and advantages will appear in the following specification, and the novel features of the device will be particularly pointed out in the appended claims.

My invention is illustrated in the accompanying drawings forming a part of this application, in which

Figure 1 is a side elevation, showing the device attached to a notebook;

Figure 2 is a front elevation, showing the device attached to a page of a sidewise opening book;

Figure 3 is an enlarged plan view of a portion of the device, portions being broken away for clarity;

Figure 4 is a section along the line 4—4 of Figure 2;

Figure 5 is a section along the line 5—5 of Figure 3;

Figure 6 shows the device when used in supporting a large chart or sheet;

Figure 7 is a rear view of the chart-supporting member;

Figure 8 is an end view of Figure 7 showing the clip attached to the device; and

Figure 9 is a section along the line 9—9 of Figure 6.

In carrying out my invention, I provide a supporting member 1 and this member carries a guide bar 2 which is hollow. Figure 4 shows how the support and guide bar may be constructed from a single piece of material. The guide bar has recesses 3 therein for receiving spring clips 4. The clips have enlarged portions 5 received in the guide bar 2. The enlarged portions 5 have shoulders 5a bearing against the side 2a of the guide bar and also have tongues 5b receivable in slots 6 in the side 2b. A tongue 7 is bent upwardly and bears against an off-set portion 8 on a rod 9 for holding the rod against the side 2a. A leaf spring 10 normally holds the clip 4 up against the rod 9 and this will keep the clip in open position, see Figure 4. The clips 4 have their ends curved upwardly to more readily receive material.

The rod 9 constitutes means for swinging the clips into clamping position against the support 1. The lower end of the rod has a handle 9a bent at right-angles thereto and extending through a slot 11 in the guide bar 2. The rod 9 is held against the side wall 2a by the tongues 7 and against the top wall by the clips 4 which in turn are supported by the springs 10. The off-set portions 8 also are normally held in contact with the top wall of the guide bar. Figure 4 shows the normal position of the off-set portions 8 and the clips 4. A swinging of the handle 9a through an arc of 90° will cause the rod 9 to bear against the top wall of the guide 2 and will cause the off-set portions 8 to swing away from the top wall and move the free ends of the clip 4 against the support 1, the clip fulcruming about its tongues 5b during this movement. The springs 10 will be compressed during this movement. The arm 9a is swung beyond dead center and will remain in this position until released. The springs 10 will return the clips 4 to open position as soon as the arm 9a is again swung into a parallel relation with respect to the support 1. The slot 11 extends into the top wall of the guide 2.

2, see Figure 2, and the end of the slot acts as a stop for limiting further clockwise rotation of the arm 9a when the arm is moved a slight distance beyond a substantially vertical position 5 with respect to the support. If desired, the support may be provided with roughened areas 12 that will cooperate with roughened surfaces 13 on the undersides of the clips. This will increase the gripping effect of the device on a note- 10 book or a page.

15 Figure 1 shows the device applied to a notebook indicated generally at 14. The support 1 is placed on the outer surface of one of the notebook covers 15, and the clips 4 engage with the opposite surface of the same cover when the handle 9a is swung into operative position. The back cover 15 of the notebook is held in a substantially vertical position to a supporting surface 16 by means of a link 17 that has its end 18 bent at right angles and removably received in aligned openings 19 in the lower end of the guide 2, see Figure 3. The free end of the link 17 is bent at 20 and is journaled in two slots 21 provided in a clip 22. Figure 1 shows the clip 22 removably secured to the notebook cover 15. The notebook and the device will assume the position shown in Figure 1.

20 The line indicator comprises a sleeve 23 that is slidably mounted on the guide 2. Figure 4 shows the sleeve extending around four sides of the guide. A leaf spring 24, see Figure 2, is carried by the sleeve and frictionally engages with one side of the guide bar. The sleeve carries a handle 25 and an arm 26 pivots about the handle and carries a line indicator 27. A telescoping member 28 is slidably mounted on the line indicator and the line indicator has an extension 29 that constitutes a handle. The line indicator may be moved from line to line by the handle 29 and the member 28 may be extended, if desired.

25 Figure 2 shows the guide bar 2 extending a considerable distance above the upper edge of the support 1. This will permit the line indicator to be moved to the top of the sidewise opening book or notebook, if desired. The device is shown attached to a sidewise opening book 30 in Figure 2. The device may be attached to the cover 31 of the book if the thickness of the pages under the line indicator is not greater than the length 30 of the pivoted arm 26. I have shown the device attached to one of the pages 32 of the book. The telescoping member 28 may be moved for extending the overall length of the line indicator over the adjacent page 32' of the book, if desired. The extension 28 can also be used when copying from a magazine column when the column is beyond the end of the line indicator 27. When the device is attached to the page 32 of the book, the line indicator may be used for copying 35 information from the page and then if it is desired to copy data from the opposite side of the page, the page may be turned and it will carry the device therewith. Before the page is turned, the sleeve 23 is moved to the top of the guide 2 and then the arm 26 is swung so as to carry the line indicator 27 over the top of the guide and down onto the other side. When now the page is turned, the line indicator can be used for following the copy, line by line on the opposite side 40 of the page. After the opposite side of page 32 is copied, the device may be removed from the page and secured to the next page. The link 17 may be removed from the device when copying from a sidewise opening book.

45 75 In Figures 6 to 9 inclusive, I show the device

adapted for copying data from a large chart or sheet of paper. The notebook is shown at 14 and the device is clamped to the covers of the notebook in the same manner as already indicated. All of the pages of the notebook are 5 turned so as to overlie only the rear cover and this will permit a chart 33 to be placed on the notebook cover and be clamped in position by the clips 4. The arm 9a is shown swung into operative position.

10 The portion of the sheet 33 that extends beyond the notebook cover is supported on its rear surface by a bar 34 that is slidably received in a guide 35 which in turn is secured to a clip 36. The clip and guide are shown in full size in Figures 7 and 8. The bar 34 is provided with a double bend 37 so as to position the bar against the back of the sheet 33 as shown in Figure 9. The clip 36 is shown secured to the notebook cover so as to dispose the bar guide 35 at the 20 rear of the cover. The clip may be secured directly to the support 1 if desired, as shown in Figure 8. The clip 36 has spring qualities that 25 yieldingly hold the bar in adjusted position on the notebook cover or support 1. The bar may also be adjusted longitudinally in the guide 35.

30 The line indicator 27 carries the telescoping member 28 and this member is extended beyond the end of the indicator and receives an extension bar 38, see Figures 6 and 9. The bar 38 35 cooperates with the line indicator 27 to form an elongated line indicator that will reach across the entire width of the sheet 33. The sleeve 23 is moved along the guide 2 in the usual manner to raise and lower the extended line indicator.

35 As a further means of permitting a person to copy data from only a single column 39 on the sheet 33, I provide an auxiliary line indicator 40 that has clips 41 designed to straddle the line indicator 27, the telescoping member 28, or the extension bar 38 in the manner shown in Figures 6 and 9. The auxiliary line indicator has a horizontal portion 42 which extends across the width of a column 39 and has a vertical portion 43 that will conceal the data in the adjoining column and thus prevent it from becoming accidentally copied. The operation of the structure shown in Figure 6 will be clearly apparent from this description. The auxiliary line indicator or column guide 40 may be reversed in its position, if desired.

40 It is possible to place a large sheet so that its longer edge is in a vertical position rather than a horizontal one. In this case, the clip 36 could be secured to the lower edge of the 55 notebook cover so that the guide 35 would be on the front face of the cover. The bar 34 would extend upwardly along the front face of the notebook cover when the clip was secured thereto so as to support the full height of the sheet. The bar 34 would be placed in the guide 35 so as to position the bent portion 37 above the notebook. The line indicator could be moved to the top of the guide bar 2 and then the arm 27 could be swung into a position above the sleeve 24 and thus permit copying to be done on a portion of the sheet disposed above the top of the guide bar.

45 I claim:

1. A line indicator designed to be attached to 70 a page of a sidewise opening book and comprising a supporting member adapted to contact with one face of the page and having a guide bar adapted to contact with an edge, clips carried by the bar, manually actuated means for 75

moving the clips toward the member for gripping the page between the member and the clips, a sleeve slidable along the bar, an arm pivoted to the sleeve, a line indicating member carried by the arm, said sleeve being movable to the top of the bar to permit the arm to be swung for disposing the line indicating member on the opposite side of the supporting member, whereby both sides of the page may be copied without the necessity of removing the line indicator.

2. The combination with two semi-rigid hinged members, a line indicator comprising a guide bar having clips for removably securing it to one of the members, a link connected to the bar, a clip secured to the free end of the link and secured to the other member for holding the two members in a tented position, said first-named clips being adapted to hold a large sheet of paper to the first-mentioned hinged member, an auxiliary clip secured to the same hinged member and carrying a guide, a bar supported by the guide for in turn supporting the back of the large sheet, a sleeve slidable on the guide bar, an arm pivoted thereto, a line indicating member carried by the arm, an extension slid-able on the line indicating member, and a bar carried by the extension.

3. The combination with two semi-rigid hinged members, a line indicator comprising a guide bar having clips for removably securing it to one

of the members, a link connected to the bar, a clip secured to the free end of the link and secured to the other member for holding the two members in a tented position, said first-named clips being adapted to hold a large sheet of paper to the first-mentioned hinged member, an auxiliary clip secured to the same hinged member and carrying a guide, a bar supported by the guide for in turn supporting the back of the large sheet, a sleeve slidable on the guide bar, an arm pivoted thereto, a line indicating member carried by the arm, an extension slid-able on the line indicating member, and a bar carried by the extension, or last-named bar.

4. The combination with two semi-rigid hinged members, of a line indicator comprising a guide bar, means for securing the bar to one of the members, a link operatively connected to the bar and having means for removably securing its free end to the other member for holding the two in a tented position, said first-named means being adapted to hold a large sheet to the first-mentioned hinged member, an auxiliary clip secured to the same hinged member and carrying a bar for supporting the back of the large sheet, and a line indicator for the sheet and slid-able along the guide bar.

BONNIE E. VAN ALSTYNE. 20
